WINDOW CONSTRUCTION

Rudolf Benzenberg, New York, N. Y.

Application August 26, 1937, Serial No. 160,955

2 Claims. (Cl. 20—42)

This invention relates to improvements in window construction, as for instance disclosed in my Patent No. 2,026,119 of December 31, 1935, and it is the principal object of this invention to simplify the construction of the window by providing a simple braking device gradually braking the movements of the window sashes which may be readily and inexpensively installed in any window.

Another object of my invention is the provision of a window construction the sashes of which are tilttable and turnable at an angle to the window frame about pivot pins near their lower ends sliding within the groove of the window frame in which the chains attached to said pin are traveling with the same.

A further object of my invention is the provision of a window construction in which the sashes in their tilted position are held in any of their adjusted locations by means of a metal mounted brake strip pivotally attached at its upper end to a wall of a chamber within the window frame and suitably outwardly pressed by means of springs conveniently located in bores arranged in the window frame.

These and other objects and advantages of my construction and invention will become more fully known as the description thereof proceeds, and will then be specifically defined in the appended claims.

In the accompanying drawing forming a material part of this disclosure:

Fig. 1 is a longitudinal section through a window construction embodying my invention.

Fig. 2 shows in fragmentary, sectional perspective view a window construction according to my invention.

Fig. 3 is a section on line 3—3 of Figure 1.

As illustrated, my improved window construction includes the customary window casing or frame 10 in which the window sashes 11 and 12 are slidably mounted for vertical reciprocation and suspended from the chains 13 guided over rollers 14 and within a suitable groove 15.

It will be understood that the window itself may have any other of the conventional constructions suitable for the installation or embodiment of my invention. The sash frames are of the vertically engaging type provided with engaging shoulders 16, 17 at their meeting frame bars.

The pivot pins about which the sash frames turn, are designated 18, and carry eyes 19 to which the ends of the chains 13 are attached and sliding in the grooves 15. In the guard or

guide strips 20 for the sashes, cut-away portions 21 are formed adapted to be covered by a cover 22 hinged to the window frame or casing. In the window frame, near the lower end thereof a longitudinally extending chamber or groove 23 is provided carrying in its inner wall depressions or bores 24, 25 within which springs 26, 27 are located extending with their outer ends into the chamber 23 and bearing with their outer ends against the inner face of a brake strip 28 pivoted at its upper end, as at 29, to the inner wall of the chamber 23 and exerting a substantially wedge action against the sash frames as the lower ends of the brake strip under the action of the springs project beyond the outer edge of the window frame, the sill 31 of which has a groove 30 formed therein to limit the movements of the lower end of the brake-strip.

A suitable handle 32 on the sashes serves to facilitate the operation of the same and eventually, as for instance disclosed in my above named patent, to operate a latch to lock the sashes against movement.

The operation and use of my invention will be entirely clear from the above description thereof by having simultaneous reference to the drawing, and it will be clear that the spring-pressed braking-rod or bar owing to its being outwardly pressed by means of the springs at its lower end and being brought into frictional engagement with the sash frame bar of the respective sash, will brake the downward movement of the same and hold it in any of its adjusted positions at a desired height relatively to the window casing. The sashes being pivoted near their lower ends can be tilted at a generous angle to the window casing to guarantee a maximum of ventilation and to allow a convenient cleaning of the window from the inside of a building, while the chains having their ends attached to the pivot pins will travel with the same in the grooves intended therefor.

It will be understood that I have described and shown the preferred form of my invention only as one example of the many possible ways to practically construct the same, and that I may make such changes in its general arrangement and in the construction of its minor details as come within the scope of the appended claims without departure from the spirit of my invention and the principles involved.

Having thus described my invention, what I claim as new, and desire to secure by Letters Patent is:

1. A window construction comprising a tilttable

sash pivoted near its lower end to the window casing, said casing having a chamber, a strip pivoted at its upper end to one wall of said casing and springs in bores of said casing walls engaging with their outer ends the lower end of said strip to press the same against the sash frame in order to exert a braking action by frictionally engaging said sash frame to hold the sash in its adjusted positions when tilted a certain amount relative to the window casing.

5. 2. In a window construction as described including a tilttable sash, a chambered and recessed

window frame, means permitting the sash to tilt, a strip in the chamber of said window frame pivotally secured thereto at its upper end, and means in the recesses of the window frame bearing with their outer ends against the inner face 5 of the strip to engage the same with the window sash with a braking action co-operating with said sash pivot means to hold the sash in its adjusted positions when tilted a certain amount relative to the window casing, and a means to limit the 10 outward movement of said strip.

RUDOLF BENZENBERG.
